UNITED STATES PATENT OFFICE.

FRITZ VON STEPSKI AND ERICH STERZINGER, OF TRIESTE, AUSTRIA-HUNGARY.

MAGAZINE FIRE-ARM.

SPECIFICATION forming part of Letters Patent No. 393,406, dated November 27, 1888.

Application filed May 18, 1888. Serial No. 274,342. (No model.)

To all whom it may concern:

Be it known that we, FRITZ VON STEPSKI and ERICH STERZINGER, both of Trieste, in the Empire of Austria-Hungary, have invented 5 certain new and useful Improvements in Magazine Fire-Arms; and we do hereby declare that the following is a full, clear, and exact description of the same.

Our invention relates to that class of breech-loading and magazine fire-arms in which the breech-block slides backward and is operated by a lever, and particularly to that class in which the breech-block consists of a longitudinally-reciprocating bolt or plug.

15 The invention is particularly described in the following specification, and illustrated in the accompanying drawings, in which—

Figure 1 is a longitudinal vertical sectional view of the working parts of a gun embodying 20 our improvements. Fig. 2 is a longitudinal vertical sectional view of the breech-bolt and the hammer and firing-pin. Fig. 3 is a longitudinal horizontal sectional view of the lock-plate and magazine-box. Fig. 4 is a longitudinal vertical sectional view of the same. Fig. 5 is a detail perspective view of one of the slide-blocks. Fig. 6 is a detail perspective 25 view of the forked lever for operating the breech-bolt. Fig. 7 is a longitudinal horizontal sectional view of a portion of the lock-plate and the breech-bolt and hammer. Fig. 8 is a view of the inner side of the plate which forms the cover of the magazine-box, and Fig. 8^a is a longitudinal sectional view of the same. Fig. 30 9 is a transverse vertical sectional view of a portion of the stock and magazine-box. Figs. 10 to 16, inclusive, are detail views, herein-after more particularly referred to.

The lever mechanism for operating the 40 breech-bolt is represented by the letters A B C. The part A B is a lever of the first kind, having its fulcrum at a fixed point, a^x , in the lower part of the lock plate or casing A^x. The stock A^{x²} is secured to the casing by a bolt 45 passing through it and through the rear extensions, R and m', and the barrel B^{x²} is screwed into the front end of the casing. The lever A B is operated by the trigger-guard C, the front end of which is pivoted at b^x to the end of the 50 arm B of the lever. The near end of the trigger-guard C is arranged to slide in a slot, k, of the

extension R, and is provided with a T-head, r, to prevent downward displacement.

The arm A of the lever is divided into two branches, and each branch is again divided or 55 forked, as shown in perspective in Fig. 6. These forked branches engage with studs i on two connecting links or bars, D, the form of which is shown in perspective in Fig. 5.

The links or bars D are connected by pivots 60 d to the sides of the breech-bolt K, which slides in ways w in the casing A^x. The trigger-guard C is provided about midway of its length with a hole, c, for the reception of the finger of the operator. To operate the lever mechanism, the trigger-guard C is grasped by the thumb and fingers, with the second finger in the hole c, and the first finger lying about parallel with the length of the trigger-guard. The parts being in the position shown in full lines in 70 Fig. 1, the forward movement of the trigger-guard throws the forked end of the lever A backward to the position shown in dotted lines, and by the connection of the lever with the links or bars D the breech-bolt K is moved 75 backward and the breech is opened to permit of the ejection of the empty shell and the insertion of a fresh cartridge.

The hammer and firing-pin consists of a spindle, H, working longitudinally in a cylindrical recess in the breech-bolt K. The front end of the spindle forms the firing-pin h^x, which works in a seat in the front end of the bolt K. About midway of the length of the spindle is a collar, o, which forms the abutment for one 85 end of a spring, h, surrounding the spindle, the other abutment of which is formed by a plate or cap which closes the rear end of the cylindrical recess and is secured by a screw, k'.

The rear end of the spindle H projects 90 through the center of the plate or cap and is provided with a milled or roughened thumb-piece, H', by means of which the spindle may be drawn backward by the thumb and finger independently of the lever mechanism. When 95 the spindle is thus independently drawn back, the links or bars D drop of their own gravity and work in recesses l in the sides of the casing A^x, with the studs i working loosely in the forks of the levers A, so that said devices do 100 not interfere with each other.

On the under side of the spindle H, between

the collar *o* and the front end, is a longitudinal rib from which project downward two fins, *L* *N*, for engagement with the sear. The fin *N* is hooked or projecting toward the front, and 5 constitutes the "half cock notch," and the fin *L* forms a right angle at its front end and constitutes the "full cock notch" or shoulder for engagement with the sear.

The trigger *G* is pivoted at the point *g* in 10 the lock plate or casing *A*^x. The cam faced upper edge of the trigger engages with the long arm of a bent lever, *F*, which has its fulcrum in the post *E*^x, and has its short arm pivoted to the lower end of the sear *E*. The upper end of the sear *E* is hooked rearward for 15 engagement with the half-cock notch or hook *N*, and is of course equally adapted for engagement with the full-cock notch or shoulder *L* in the usual way. When the sear is engaged 20 with the half cock notch *N*, it is impossible to explode the cartridge, either accidentally or otherwise, because of the engagement of the hooked portions of the sear and the fin; but when engaged with the full-cock notch or fin 25 *L* the hammer and firing-pin can be released by pulling the trigger.

The sear is pressed upward by the spring *E*^x, which holds it always in position for engagement with the half-cock and full-cock fins.

30 The extractor consists of a V-shaped spring, *M*, arranged in a recess in the front portion of the breech-bolt *K*, with its lower arm projecting beyond the front end and formed with a hook, *a*, for engagement with the flange of 35 the cartridge-head.

The operation of the parts above described is as follows: When the trigger-guard *C* is moved forward, the forked lever *A*, by its engagement with the links or bars *D*, as above 40 described, forces the breech-bolt *K* backward until said lever is in the position shown in dotted lines, during which movement the hook *a* of the extractor *M*, by its engagement with the rim of the cartridge-shell, withdraws said 45 shell from the chamber of the breech and carries it backward until the breech-bolt has reached the limit of its backward movement, when the front end or point of the firing-pin *h*^x strikes the heel of the shell and ejects it 50 through an opening in the casing in the usual and well-known manner. This operation is the same in all cases, whether the gun is used as a magazine or as a single-loader. When the gun is to be used as a magazine-arm, the 55 magazine is secured in place in the position shown in Figs. 1 and 9. When used as a single-loader, the magazine is removed and a plate inserted in its place, as hereinafter more particularly described. The magazine *T* is 60 carried by the magazine-box *T*^x, which is suspended from the under side of the lock plate or casing *A*^x, as shown in Figs. 1 and 9, and is held in place by screws or other suitable means, so that it can be readily removed when 65 desired.

In the bottom of the magazine *T* rests the carrier, which consists of a plate *x*, (see Fig.

14,) bent longitudinally and having an upward curve toward the front end to correspond with the general form of the cartridges, and 70 so that said cartridges may lie in alternately higher and lower planes and partially overlap each other, as shown in Figs. 1 and 12. To the under side of the rear end of the carrier *x* is attached a box or barrel, *n*^x, which surrounds a helical spring, *n*², the lower end of 75 which bears against the bottom of the magazine and the upper end bears against the bottom of the carrier in order to raise it to feed the cartridges to the chamber of the barrel. 80

On one side of the magazine-box *T*^x is a casting or enlargement, *t*^x, in which works a lever, *m*, pivoted in lugs *m*², and having at the upper end a hook or catch, *s*, and at the lower end a button or stud, *t*, which projects through a 85 hole slightly beyond the outer surface of the casing. Inside of the casing is a spring, *m*, which bears against the upper end of the lever and presses it inward, so as to cause the hook or catch *s* to engage with ratchet-teeth *n* and *u* 90 on the side of the magazine *T*. When the gun is used as a magazine-arm, the hook or catch *s* is engaged with the tooth *u*, so that the top of the magazine *T* is below the level of the ways *w*, as shown in Fig. 9, and when the breech-bolt *K* is thrown back to open the breech the 95 cartridges are free to rise when pressed upward by the carrier spring *n*, so that by the forward movement of the breech-bolt a cartridge may be inserted in the chamber of the 100 breech.

When the magazine is to be removed, in order to refill it or for any other purpose, by pressing on the button *t* the catch *s* is disengaged from the tooth *u*, so that the magazine 105 may be raised, by the upward pressure of the spring *v*, to such a position that it may be lifted out of the magazine-box through the open breech.

When the gun is to be used as a single-loader, 110 the feeding-plate *P*² (shown in Figs. 8 and 8^a) is inserted in the open breech above the magazine-box, and may be secured in place by means of screws passed through lugs at its ends or in any other suitable manner. The 115 plate *P*² is of skeleton form, and has suspended below it a bowl, *P*', the top of which corresponds with the level of the chamber of the breech sufficiently near to allow a cartridge placed in said bowl to be inserted in the chamber of the breech by the forward movement of the breech-bolt *K*, as above described. 120

When the gun is to be used only as a single-loader, the magazine may be entirely removed and may be carried separately from the gun, 125 and, if desired, it may be charged with cartridges, so as to be ready for immediate use when inserted in place.

When the magazine is charged and in place in the magazine-box, if it is desired to hold the 130 magazine in reserve and use the gun as a single-loader, the magazine is pressed downward in the magazine-box (see Fig. 9) until the hook or catch *s* engages with the uppermost

ratchet-tooth, *n*, by which means provision is made for the reception of the feeding-plate *P*² and its bowl *P'*, so that the cartridges may be fed singly to the chamber of the breech without interfering with the operation of the magazine.

What we claim as new, and desire to secure by Letters Patent, is—

1. In a repeating fire-arm, the combination of the lever mechanism consisting of the double-forked lever *A* *B* and the trigger-guard *C*, having its front end pivoted to said lever and its rear end provided with a *T*-head and sliding in a slot of the extension *R*, with the links or bars *D*, provided with studs *i* and pivots *d*, and the rectilineally-sliding breech-bolt *K*, said links or bars *D* engaging the breech-bolt *K* and the forked lever *A*, respectively, by means of the pivots *d* and studs *i*, for opening and closing the breech, substantially as shown and described.

2. The magazine-box *T*², provided with the casing *t*² on one side inclosing the spring *m* and lever *s* *t*, and carrying the carrier-spring *n*² and magazine-spring *v*, in combination with the magazine and carrier, substantially as herein described.

3. The magazine *T*, provided with the teeth *n* and *u*, in combination with the magazine-box *T*², provided with the spring *m* and lever *s* *t*, and carrying the magazine-spring *v*, whereby provision is made for holding the magazine in place in the magazine-box and for removing it when desired, substantially as herein described.

4. The combination, with the magazine *T*, of the carrier *x*, consisting of a plate bent longitudinally and having an upward curve toward the front end to correspond with the gen-

eral form of the cartridges, and of a width sufficient to hold a layer of cartridges side by side, with a number of layers of cartridges above the lowest layer all arranged to lie in alternately higher and lower planes and partially overlap each other, said carrier being provided with the box or barrel *n'*, inclosing the spring *n*², substantially as and for the purpose herein described.

5. The combination, with the magazine *T* and magazine-box *T*², of the coiled spring *n*², inclosed in the box or barrel *n'*, and having its ends bearing respectively against the bottom of the magazine and the bottom of the carrier, and the coiled spring *v*, having its ends bearing respectively against the bottom of the magazine and the bottom of the magazine-box, substantially as and for the purpose herein described.

6. The combination, with the hooked fin or half-cock notch *N*, of the trigger *G*, pivoted at *g*, the elbow-lever *F*, having its fulcrum in the post *E'*, and having its long arm engaged by the cam-faced upper edge of the trigger, and the hooked sear *E*, pivoted to the short arm of the lever *F* and pressed upward by the spring *E'*, all arranged and operating as herein shown and described.

In witness whereof we hereunto set our hands in presence of two witnesses.
